UNITED STATES PATENT OFFICE

123,066

DESIGN FOR A DOLL

Mary Belle Reeder, Miami, Fla.

Application August 3, 1940, Serial No. 94,174

Term of patent 14 years

To all whom it may concern:

Be it known that I, Mary Belle Reeder, a citizen of the United States, residing at Miami, in the county of Dade and State of Florida, have invented a new, original, and ornamental Design for a Doll, of which the following is a specification, reference being had to the accompanying drawing, forming part thereof.

I claim:

The ornamental design for a doll, as shown.

MARY B. REEDER.
